ELASTIC EXERCISER

Benny W. Davis and Carl H. Owens, Jacksonville, Fla.,
assignors to Owens Chemical Co., Inc., Jacksonville,
Fla.

Filed Apr. 28, 1971, Ser. No. 138,397

Term of patent 3½ years

Int Cl. D21—02

U.S. Cl. D34—5

FIG. 1

FIG. 2

FIG. 3

FIG. 4

FIG. 1 is a front elevational view of the elastic exerciser showing our new design;

FIG. 2 is an enlarged cross-sectional view taken along line 2—2 of FIG. 1;

FIG. 3 is an enlarged cross-sectional view taken along line 3—3 of FIG. 1; and

FIG. 4 is an enlarged sectional view taken along line 4—4 of FIG. 1.

We claim:

The ornamental design for an elastic exerciser, substantially as shown.
